UNITED STATES PATENT OFFICE.

GEORGE W. COOPER, OF NEW YORK, N. Y.

GAME APPARATUS.

1,247,645.

Specification of Letters Patent. Patented Nov. 27, 1917.

Application filed March 20, 1915. Serial No. 15,701.

To all whom it may concern:

Be it known that I, GEORGE W. COOPER, a citizen of the United States, and a resident of the city and State of New York, 5 have invented certain new and useful Improvements in Game Apparatus, of which the following is a specification.

This invention relates to certain improvements in game apparatus and more particularly in that class of such apparatus which involve the use of a target member at which projectiles are to be discharged and the object of the invention is to provide an apparatus of this general character having a 10 novel and improved construction and arrangement of target devices together with novel and improved means for discharging projectiles thereat whereby accurate aim is afforded in order that skill may be developed in such a way as to add interest to the 15 game.

The invention consists in certain novel features of the construction and combinations and arrangements of the several parts 20 of the improved game apparatus whereby certain improved advantages are attained and the apparatus is rendered simpler, less expensive and otherwise better adapted and more convenient for use, all as will be herein 25 after set forth.

The novel features of the invention will be carefully defined in the claims.

In order that my improvements may be the better understood, I will now proceed 30 to describe the invention with reference to the accompanying drawings, wherein—

Figure 1 is a perspective view showing target devices embodying my present invention;

Fig. 2 is a side elevation partly in section 35 illustrating one embodiment of the improved means for discharging projectiles at the target devices;

Fig. 3 is a plan view of the devices shown 40 in Fig. 2;

Fig. 4 is a fragmentary view somewhat similar to Fig. 2 but showing certain of the operative parts in differently adjusted positions;

Fig. 5 is a fragmentary sectional view 45 illustrating a modified formation of the means for holding the separable target members in place upon the base member or chart, and

Fig. 6 is a fragmentary view illustrating 50 a modified formation of the projectile dis-

charging means comprised in my present invention.

As shown in these views the improved game apparatus comprises a chart or base 60 member 1 of which two or more may be provided dependent upon the number of persons playing the game, and which as herein shown is made in the form of a flat rectangular sheet of pasteboard or similar material having produced upon it the outline 2 of a harbor or equivalent subject-matter, there being positions or stations marked by suitable insignia as indicated at 3 adjacent to the outline of said harbor at which rectangular shields or squares of pasteboard or the like indicated at 4 are to be detachably supported.

The chart or base member is also provided with other characters or insignia produced 75 thereon as indicated at 5 in the drawings at which other target devices 6 are to be detachably supported, these latter target devices as herein shown also formed from pasteboard or other suitable material and 80 being shaped or fashioned to represent battleships or soldiers, etc., which may be considered to be acting in connection with fortifications represented by the shields or squares 4 for the protection of the harbor or 85 fort or the like indicated at 2 upon the chart or base member. Where a plurality of the charts or base members are provided, they may be similar to each other in size and outline so that they may be conveniently 90 packed in a pasteboard or other box, which may also be utilized as a container for the other parts of the game apparatus, and when this is done the cover and body of the box may be erected back of the charts or base 95 members as indicated at 6 on the drawings, to afford back grounds to be struck by projectiles discharged at the target devices to prevent the same from becoming lost.

In order to locate the target devices 4 and 100 6 upon the charts or base members, the indices or equivalent devices 3 and 5 may be located in different angular positions as clearly indicated in Fig. 1, whereby the target devices are caused to stand at angles to 105 the direction of the projectiles to render them less easy of being struck and require greater accuracy of aim in playing the game. One or more of the indices as indicated at 3^a on the drawings may also be located in the 110 rear of the shields 4, 4 so that the target device 6 erected thereon will be protected from

the projectiles by said shields until after the latter shall have been overturned or displaced by the projectiles.

In applying the target devices 4 and 6 upon the charts or base members various means may be provided for holding them removably in position until struck by the projectiles. In Fig. 1 I have shown the target devices 4 and 6 provided for this purpose 10 with pins 8 extended downwardly through them having their points adapted to penetrate the charts or base members in such a way as to hold the target devices in erect position thereon but it will be obvious that 15 other means may be provided for this purpose as, for example, that shown in Fig. 5 of the drawings wherein the chart or base member 1 is provided with upwardly extended pointed pins 9 which may penetrate the 20 lower edge portions of the target devices to hold them in erect positions. In applying the target devices to the charts or base members it may be preferable to permit each player to apply the target devices to his 25 opponent's chart or base member 1 so as to insure against such extreme penetration of the pins as would interfere with the overturning or displacement of the target devices when struck by the projectiles. Dice 30 or some other equivalent means may be provided for determining the positions in which the several target devices are to be applied to the charts and to facilitate the use of such means I have shown the indices 5 provided 35 with members 5^a which may correspond with the members indicated by the dice when thrown in a well-known way.

In connection with the target devices above described my invention also comprises 40 an improved gun for discharging projectiles, one of which discharging devices may be provided for each of the players. As herein shown the discharging means is made in simulation of a gun 10 mounted upon a 45 carriage 11. The gun and its carriage may be produced with convenience from wood in two pieces for the sake of economy glued together or otherwise joined along the line indicated at 12 and to support the device I 50 have shown the same provided with a flattened base 14 also of wood or the like having upturned dowels 15 adapted for detachable engagement in apertures in the lower part of the member 11 so as to support the device 55 in erect position upon a table or the like in order that aim may be taken by each player for accurately discharging the projectiles toward his opponent's target devices.

As herein shown the gun is adapted to be 60 loaded with two projectiles for which purpose it is provided with duplicate projectile holding and releasing means arranged side by side and separated by a groove 16 produced in the upper surface of the gun 10 as 65 clearly indicated in Fig. 3. The projectile

holding means comprises a raised rib or bead 17 extended longitudinally of the gun barrel having abutments 18 and 19 at its forward and rear extremities so that said rib or projection is adapted to receive a rubber band 20 suitably stretched or elongated to place it under tension and permit it to be stretched from the forward abutment 18 with which one of the ends of the band is engaged to the rearmost abutment 19 with which the opposite end of said band is engaged as clearly indicated in Figs. 2 and 3. At the rear abutment each projectile holding means is provided with a central upwardly extending curve or groove 21 in 80 which is engaged the forward bent end 22 of a trigger 23 constituting the projectile releasing means and pivoted at 24 upon the side of the gun.

25 represents a spring engaged with the trigger and exerting its tension to hold the same normal with its bent forward end portion 23 depressed toward the base of the groove or curve 21 as indicated in dotted lines in Fig. 2 so as to be positioned beneath the rear end of the band or projectile 20 and in position to engage and lift the same, when the trigger is moved pivotally so that the rear end of the elastic band or projectile is released from the rearmost 95 abutment 19 of the corresponding bead or rib 17 in order that its tension may be exerted to cause the same to spring forward and be discharged toward the target devices at which aim has been taken. For conveniently operating the triggers they are provided with upwardly extended thumb pieces 26 adapted to be readily engaged by the player's finger in order to rock said triggers upon their pivots, the springs 25 serving automatically to retract the triggers into lowered positions after the projectile is discharged.

To facilitate aiming the gun in order that the barrel may be elevated or depressed 110 as conditions may require I have shown the same provided with a detachable wedge-shaped part 30 adapted to be inserted beneath the rear or forward end of the base plate 14 in such a way as to elevate or depress the barrel of the gun at such an angle as may be necessary to assure accurate aim. The elevating member being detachable may be readily packed within the container with the remaining parts of the apparatus. The 115 base member 14 being detachable from the body portion of the gun is also capable of being readily packed within the container.

The projectiles employed may be ordinary rubber bands of any desired size and 120 strength and in certain cases where the bands are too light they may be twisted repeatedly around the ribs or beads 17 in order to assure greater or less tension and consequently increase or lessen of the 130

trajectory and may be knotted or weighted at the end or ends if found necessary in judgment of player to insure strength and accuracy.

5 From the above description it will be seen that the improved game apparatus constructed according to my invention is of an extremely simple and comparatively inexpensive nature and is particularly well
10 adapted for use by reason of the skill required for successfully playing the game and of the absolute safety attained by the employment of rubber bands in lieu of other projectiles such as have been heretofore employed in connection with game apparatus and it will also be obvious from the above description that the game apparatus is capable of some modification without material departure from the principles and
15 spirit of the invention and for this reason I do not desire to be understood as limiting myself to the precise formation and arrangement of the several parts herein set forth in carrying out my invention in practice. For example, the target devices may represent a city or other position to be defended and the projectile discharging means may be in the form of a pistol, shoulder arm or other arm different from that
20 herein shown.

25 In Fig. 6 I have also illustrated a modified formation of the projectile discharging means in which the rear abutment 19^a for maintaining the rubber band under tension is carried upon the upper end of the trigger 23^a so as to be adapted to be disengaged from the rubber band when the trigger is
30 actuated by the player's finger.

Having thus described my invention, what I claim and desire to secure by Letters Patent is—

1. In game apparatus, a gun having spaced abutments adapted to be engaged by the opposite ends of an elongated rubber band, one of said abutments having a slot crossed by one end of said band, and a trigger pivotally supported and having a forwardly directed portion normally seated in said slot beneath said band, and engageable with said rubber band, when the trigger is moved pivotally to release said end of the rubber band from said slotted abutment when the trigger is actuated.

2. In a device of the character described, a body portion having a central longitudinal groove affording at its opposite sides elevated parts provided with spaced abutments at their opposite ends, the abutments of each elevated part being adapted to be engaged by the opposite ends of a rubber band to hold the same under tension, and said longitudinal groove being of a width adapted to permit the lateral parts of said rubber bands to be extended therein side by side, and means for releasing a band from the abutments of each elevated part independently of the release of another band engaged with the abutments of the other elevated part.

In witness whereof I have hereunto signed my name in the presence of two subscribing witnesses.

GEORGE W. COOPER.
